UNITED STATES PATENT OFFICE.

LESLIE LONG, OF SUBLLETTE, ILLINOIS.

CAR-COUPING.

SPECIFICATION forming part of Letters Patent No. 258,086, dated May 16, 1882.

Application filed February 14, 1882. (No model.)

To all whom it may concern:

Be it known that I, LESLIE LONG, of Sublette, in the county of Lee and State of Illinois, have invented a new and useful Improvement 5 in Car-Couplings, of which the following is a full, clear, and exact description.

This invention consists in a novel construction, arrangement, and combination of a draw-head, spring-levers provided with studs or 10 catches, and means for operating the said levers, as hereinafter more particularly described.

Reference is to be had to the accompanying drawings, forming part of this specification, in which similar letters of reference indicate 15 corresponding parts in all the figures.

Figure 1 is a longitudinal vertical section of a coupling embodying my improvements. Fig. 2 is a top view of the same, and Fig. 3 is 20 a perspective view of the form of coupling-bar used in coupling a car provided with the old style of draw-head to one provided with my invention.

A is a draw-head, having its rear end provided with a draw-bar, a, working in a frame, 25 B. To the inner end of this draw-bar a is attached a piston, a², which slides in the frame B and guides the end of the draw-bar a. A partition, b, divides the frame B into two compartments, and is provided with a hole in the 30 middle, through which the draw-bar a slides. This partition b serves as abutments for the inner ends of spiral springs b² and b³, which are intended to prevent injury to the draw-bar by sudden jars. The rear end of the spring 35 b² bears against the piston a², and the front end of the spring b³ bears against a shoulder, b⁴, on the draw-bar a.

The draw-head A is provided with two rock-shafts, C, having bearings in the upper and 40 lower sides of the mouth of the draw-head, which shafts form the fulcrums for levers D, attached to them. To the outer ends of these levers are pivoted pins d, which slide in holes in the draw-head A. The inner ends of these 45 pins are tapered and bent slightly backward to form hooks d². Spiral springs d³ surround the pins d, between the levers D and the top and bottom of the draw-head A, to keep the hooks d² projected toward each other and into 50 the mouth of the draw-head A.

The inner ends of the levers D are provided

with ropes or chains c, which are attached to a shaft or windlass, F. This shaft has bearings in the draw-head A, and is braced at its outer end to the body of the car I by a V-shaped brace, H. The said shaft is provided with a hand-wheel, G, at its outer end, and also with a ratchet-wheel, f, on the shaft, and a pawl, f², carried by the brace H.

The coupling-bar E is made preferably in 60 the form shown in Fig. 1, having a double hook or barb, e², formed at each end, and on each side, behind the barb, protuberances e³. The link may, however, be made as shown in Fig. 3, having a barb on one end and a link 65 on the other for coupling to ears provided with the old-fashioned link-and-pin couplings. The link may also be made with both a barb and a slot at each end.

The operation of my invention is as follows: 70 When the cars are being coupled the coupling-bar E, being already held in the draw-head of one car, is forced into the draw-head of the other car between the hooks d², which, after the barbed part of the coupling-bar passes 75 them, are immediately forced into their former places by the springs d³, and prevent the coupling-bar from being withdrawn. When it is desired to uncouple a car the shaft F is turned by means of the wheel G or a crank, 80 which winds up the chains c and draws the inner ends of the levers D nearer together, thus withdrawing the hooks d² from engagement with the coupling-bar, and allowing it to be withdrawn from the draw-head. When 85 for any reason it is desired to retain the hooks d² in this position the pawl f² is engaged with the ratchet-wheel f, and prevents the shaft F from revolving.

The advantages of my invention are greater 90 steadiness of the coupling-bar in the draw-head, both when coupled and uncoupled, greater strength and durability of the coupling-bar, and greater facility in coupling than heretofore.

Having thus fully described my invention, I claim as new and desire to secure by Letters Patent—

1. In a car-coupling, the combination of a coupling-bar, E, formed, as above described, 100 with a draw-head, A, provided with levers D, having pivoted hooks or studs d² and springs

d^3 , substantially as and for the purpose herein set forth.

2. In a car-coupling, the pivoted and spring-pressed levers D, provided with the pivoted hooks or studs d^2 on their outer ends, in combination with the draw-head A, and means, substantially as herein shown and described,

for operating the said levers, as and for the purpose set forth.

LESLIE LONG.
